US0D1078428S

(12) **United States Design Patent** (10) Patent No.: **US D1,078,428 S**
(45) Date of Patent: ** Jun. 10, 2025

(54) **ABRASIVE DISC**

(71) Applicant: **WALTER SURFACE TECHNOLOGIES INC.**, Pointe-Claire (CA)

(72) Inventors: **Marc Brunet Gagne**, Beauharnois (CA); **Mykolai Dutkewych**, Lachine (CA)

(73) Assignee: **WALTER SURFACE TECHNOLOGIES INC.**, Pointe-Claire (CA)

(**) Term: **15 Years**

(21) Appl. No.: **35/517,968**

(22) Filed: **Aug. 4, 2022**

(80) **Hague Agreement Data**

Int. Filing Date: **Aug. 4, 2022**

Int. Reg. No.: **DM/224564**

Int. Reg. Date: **Aug. 4, 2022**

Int. Reg. Pub. Date: **Aug. 4, 2023**

(51) **LOC (15) Cl.** **08-05**

(52) **U.S. Cl.**

USPC **D8/70**; D8/90

(58) **Field of Classification Search**

USPC D8/70, 90; D15/126

CPC B24D 7/06; B24D 18/00; B24D 11/02

See application file for complete search history.
